UNITED STATES PATENT OFFICE.

CHARLES PEGLER, OF ELGIN, ILLINOIS.

DESIGN FOR A BOOK-REST AND HOLDER FOR UMBRELLAS, &c.

SPECIFICATION forming part of Design No. 22,010, dated November 22, 1892.

Application filed October 31, 1892. Serial No. 450,582. Term of patent 14 years.

To all whom it may concern:

Be it known that I, CHARLES PEGLER, a citizen of the United States, residing at Elgin, in the county of Kane and State of Illinois, have 5 invented and produced a new and original Design for a Book-Rest and Cane and Umbrella Holder, of which the following is a specification, reference being had to the accompanying drawing, forming a part thereof, 10 in which the figure represents in perspective a combined book-rest and cane and umbrella holder embodying my new design.

The design consists in the configuration shown. Thus *a* indicates the back and *b* the ends. The lines of the ends *b* at the front *c* are straight and vertical, and at the top *d* the lines form a concave depression, the outer or rear terminal of the top line being returned, 15 as at *e*, and joining the rear vertical line *f*, 20 which latter is in the form of a double ogee which terminates about on a line with the bot-

tom line of the back *a*. Below the ogee curves the ends *b* are of bracket-like configuration, presenting openings *g*, extending from the back edge, the openings having 25 mainly circular walls or defining edges, of which the terminals curve upwardly. The lines of the bracket-like figure at the bottom of the openings present upwardly-disposed hook-like figures *h*, having knob-like figures 30 *i* at their ends. The bottom edge line *j* of each end *b* is in the form of compound curves that merge into the lines of the lower hook-like figures *h*.

I claim—

The design for a book-rest and cane and umbrella holder, herein shown and described.

CHARLES PEGLER.
